UNITED STATES PATENT OFFICE.

WARD B. STORY, OF NEW YORK, N. Y., ASSIGNOR TO AMERICAN ASSEMBLING MACHINE COMPANY, A CORPORATION OF DELAWARE.

AUTOMATIC STOPPING DEVICE.

1,261,867.

Specification of Letters Patent.

Patented Apr. 9, 1918.

Application filed November 16, 1916. Serial No. 131,675.

To all whom it may concern:

Be it known that I, WARD B. STORY, a citizen of the United States, and a resident of New York city, in the county of New York and State of New York, have invented certain new and useful Improvements in Automatic Stopping Devices, of which the following is a specification.

This invention relates to automatic stopping devices and is particularly designed to be used in connection with newspaper assembling machines although it may be used for any other purpose for which it is adapted.

In the art of assembling newspapers, and in other allied arts, in which it is necessary to feed individual objects, which may be sheets, or folded paper sections, in succession into a machine for any purpose, it is usually important to insure that no more than the required number of sheets, or folded sections, simultaneously passes through the operating mechanism. An object of this invention is to detect the feeding out of an abnormal number of objects from a feeding mechanism.

A further object of the invention is to automatically stop the operation of the machine when the feeding mechanism therefor delivers more than a normal number of objects.

Having these general objects in view, the invention consists principally in the provision of means for indicating when any one of a plurality of feeding devices, which are arranged to feed objects into a common passageway, operates to deliver more than a predetermined number of objects into the passageway in any one feeding operation.

Other features of the invention will be referred to as the description proceeds.

In the accompanying drawings in which the invention is disclosed in a concrete and preferred form, like reference characters are used to designate like parts throughout the several views.

Figure 1 is a diagrammatic view showing a preferred embodiment of the invention.

Fig. 2 is a view partly in section and partly in elevation of part of a paper feeding mechanism and shows the relation of the stop device operating mechanism thereto.

Fig. 3 is an enlarged detail view looking in the direction of the arrow along Fig. 2.

Fig. 4 is an enlarged detail view of the

specific stop device operating mechanism shown at the left-hand end of Fig. 1.

In the preferred embodiment of the invention, the device is shown in connection with an assembling machine such as is disclosed in the companion application Serial No. 131,674, filed Nov. 16, 1916. In the assembling machine feeding devices 1, 2, 3, 4, or any other desired number, are employed which are arranged to individually feed the folded paper sections into a passageway 6 leading from opposite directions to an intermediate delivery passage 39 and thence to suitable opening and assembling mechanism, not herein shown. In the operation of such a machine it is essential that only one paper section at a time be fed from the feeding devices into the passageway 6.

In order to insure that not more than one section at a time travels through the passageway means are provided which coöperate with each feeding device that will operate when two or more sections are simultaneously fed out to automatically stop the operation of the machine. This automatic stopping means comprises generally the elongated rock shaft 7 which is mounted in a parallel relation to the passageway 6 on suitable brackets 37 and which is provided at one end with a downwardly extending arm 8 which is arranged to engage and operate a circuit breaker 9 when the arm 7 is rocked. The operation of the circuit breaker has the effect of cutting off the supply of power to the motor which drives the machine.

The means for rocking the rock shaft 7 in order to thus automatically stop the operation of the machine, preferably takes two forms. One form of this operating means is shown in connection with the feeding devices 1, 2 and 4 and preferably comprises a nip roll 10 which is arranged in conjunction with the passageway 6 to operate stopping mechanism when it has been deflected to a predetermined extent by the passage of more than the normal number of paper sections thereby. In the case of the feeding device 1 the corresponding nip roll is adjusted to operate if more than one paper section passes thereby, while in the case of the feeding device 2, the corresponding nip roll may be adjusted to permit a paper section from the feeding device 1 and also the feeding device 2 to pass by in superposed relation. The nip rolls 10 are carried by the

spring pressed arms 11 and each is provided with an arm 12 which in turn is arranged to engage and turn a bell crank 13 about its axis 14 to thereby rock the rock shaft 7 through the engagement of the other end of the bell crank with an arm 15 extending downwardly from the rock shaft 7. It will be seen that by this arrangement an abnormal depression of a nip roll 10 occasioned by the 10 passage between the nip roll 10 and the feeding-out cylinder 16 of the corresponding feeding device of more than the normal number of paper sections can be arranged to operate the rock shaft 7 and consequently 15 the circuit breaker in the manner already described.

The construction whereby the nip rolls 10 are resiliently mounted includes the roll supporting arms 11 which are pivotally 20 mounted in the brackets 17 in turn mounted on the supporting rods 18 which extend from side to side of the machine and are supported in any suitable manner at the ends in the side members of the machine 25 framework and preferably so as to be vertically adjustable. The brackets 17 which support the arms 11 are provided with spring seats 20 in which the springs 21 are mounted to engage the lugs 23 on 30 the arms 11 and thereby swing the arms about their pivots and hold the nip rolls 10 in their elevated position. The arms 12 which operate the bell cranks 15 are directly supported by the roll supporting arms 11 35 and the arms 12 can be given any suitable length to cause them to extend to the rock shaft operating bell cranks 13 to accord with any convenient location in which they may be mounted.

40 Not only are the nip rolls 10 which co-operate with the feeding-out cylinders 16 of the feeding devices resiliently mounted in the manner shown, but intermediate nip rolls 24 are provided which co-operate with 45 feed rolls 25 mounted intermediately of the feeding devices themselves. The feed rolls 25 are preferably driven through the gears 26 which are in turn directly driven from gears mounted on the shafts of the feeding-out cylinders 16 of the feeding devices. These intermediate feed rolls 25 serve to 50 carry the paper sections along the passageway 6 when they have passed beyond the influence of the feeding-out rolls themselves. Preferably the nip rolls 24 are not 55 arranged to operate the automatic stopping mechanism since the provision of means co-operating with each feeding device would be ordinarily sufficient for the purpose, 60 although it is obvious that such additional means could be provided where it is found to be desirable.

The bell crank members 13 which are controlled by the feeding-out devices 1 and 2 65 and 4, and a feeding out device correspond-

ing to 1, not shown, are preferably mounted on a common portion of the framework of the machine as at 27. It will be seen that the two bell cranks at either end of the machine differ somewhat in their formation 70 because of the respective distances separating them from the corresponding nip rolls 10 from which they are operated. This difference in formation shows itself in the arm of the bell crank which is engaged by 75 the operating arm 12. In the one case this arm of the bell crank projects laterally directly from its pivot point whereas in the other case it curves outwardly in a direction parallel to the axis in order to be 80 brought to a position where it can be engaged by the end of the operating arm 12.

85 Preferably the feeding device 3 which is the most centrally located one of the group, is provided with a stop mechanism operating device of a different form than the ones described. One reason for providing a modified form of operating device in this location is because of the lack of space in which to mount an operating device of the 90 type already described. In this instance the operating device comprises a rod 28 which extends across the machine just underneath the passageway 6 and in such relation to the passageway that the guiding strips 29 95 thereof rest on its upper surface. The guiding strips 29 are supported at 30 on one of the supporting rods 18 already described and the free ends of the guiding strips 29 are unsupported except for their engagement with the rod 28. The rod 28 is supported at its end directly on the springs 30 which are in turn supported on the bolts 31 threaded into the under side of the side frame pieces. Suitable nuts 32 at the lower 100 ends of the bolts 31 provide a means for adjusting the tension of the spring 30 as needed. The rod 28 preferably passes through a slot 33 provided with a yoke 34 which is connected at its upper end with a 105 short arm 35 projecting laterally from the rock shaft 7. This connection takes the form of a bolt 36 which is threaded into the upper end of the yoke 34 and passes through the arm 35. The upper end of the bolt is 110 provided with a spring 37 which bears against nuts 38 provided at the upper end of the bolt and tends to hold the yoke 34 in its uppermost position. It will be seen that by this construction means have been provided which, when more than a predetermined number of paper sections passes through the passageway 6 at a point adjacent the bolt 28, the guide strips 29 will be depressed thus bearing down on the bolt 28 115 and moving it downwardly against the pressure of the springs 30. This downward movement of the rod 28, as will be apparent, will pull downwardly on the yoke 34 and thus turn the stop mechanism operating 120 125 130

shaft 7 about its axis to thereby break the motor circuit.

The arm 8, which directly operates the circuit breaker 9, is preferably loosely mounted on the rock shaft and is preferably moved into operative position by means of the pull spring 40 which is attached at one end to a lug 41 extending from the arm 8 and at the other end to an upward extension 10 on the arm 15. A laterally extending lug 42 from the arm 15 engages a web 43 on the arm 8 and it will be seen that the spring 40 so acts as to hold the lug 42 and flange 43 in engagement with each other. 15 It will be seen that in a movement of one of the bell cranks 13, as shown in Fig. 3, to a position which will cause the set screws 44 to engage and turn the arm 15 and rock shaft 7 in a counter clockwise direction, the 20 spring 40 will pull the arm 8 against the circuit breaker 9 and cut off the supply of power to the motor and stop the operation of the machine.

A driving means for the feeding mechanism includes the motor as shown which drives the gear train 45, 46, 47, 48 and 49. The gear 49 drives the feeding-out cylinders of the feeding devices 2 and 3, and a gear 50 drives the feeding device 1 from the 30 feeding device 2. The gears 51 and 52 convey motion from the feeding device 3 to the feeding device 4 which obviously must operate in reverse to the feeding devices 1, 2 and 3. A gear 53 preferably 35 drives a feeding device, not shown, corresponding in a general way to the feeding device 1, at the opposite end of the machine. Feeding rollers 54 and 55 serve to feed paper sections through the curved passages 40 56 and 57 leading to the delivery outlet 39. The gears 58—59 and 60—61, operate to drive the feeding rollers 54 and 55 from the feeding devices 3 and 4.

What is claimed, is:

45 1. An automatic stopping device comprising: a right-line passageway through which paper sections are to be conveyed, means for conveying paper sections through said passageway, a plurality of feeding devices arranged along said passageway and operating to feed paper sections one at a time into said passageway, means for automatically stopping the operation of said feeding devices, a rock shaft extending 50 along said passageway and adapted to operate said stopping device, and a rock shaft actuating means for each feeding device, whereby the stopping device will be operated when more than one paper section has 55 been simultaneously fed into said passage- 60

way by any one of said feeding devices to automatically stop the operation of the feeding devices.

2. Automatic stopping mechanism for a paper feeding machine comprising: a paper feeding device including a feeding-out roller, a passage into which the papers are delivered from the periphery of the feeding-out roller, a stopping device including a rock shaft extending along said passage, and 65 means for operating said rock shaft to stop the machine when more than a predetermined number of papers are simultaneously fed into said passage by said feeding-out roller, said means including a spring-pressed roller normally engaging the periphery of said feeding-out roller at the point where the papers are fed into said passage. 70 75

3. Automatic stopping mechanism for an electrically operated paper feeding machine comprising: a paper feeding device including a feeding-out roller, a passage into which the papers are delivered from the periphery of the feeding-out roller, a stopping device including a rock shaft extending along 80 said passage, a switch, an arm carried by said shaft for operating said switch, and means for operating said rock shaft to open the switch and stop the machine when more than a predetermined number of papers are 85 simultaneously fed into said passage by said feeding-out roller, said means including a spring-pressed roller normally engaging the periphery of said feeding-out roller at the point where the papers are fed into said 90 95 passage.

4. Automatic stopping mechanism for an electrically operated paper feeding machine comprising: a series of paper feeding devices each including a feeding-out roller, a 100 passage into which the papers are delivered from the peripheries of the feeding-out rollers, a stopping device including a rock shaft extending along said passage, a switch, an arm carried by said shaft for operating said 105 switch, and means for operating said rock shaft to open the switch and stop the machine when more than a predetermined number of papers are simultaneously fed into said passage by one of said feeding-out rollers, said means including a plurality of 110 spring-pressed rollers arranged to normally engage the peripheries of said feeding-out rollers at the points where the papers are fed into said passage. 115

Signed at New York, in the county of New York and State of New York this 13th day of November A. D. 1916.
